END DETECTOR FOR KNITTING MACHINES

Jacob Wachsman, Brooklyn, N. Y.

Application November 14, 1935, Serial No. 49,648

1 Claim. (Cl. 66—163)

This invention relates to improvements in end detectors for knitting machines, that is devices which are controlled by the travelling thread and are arranged to close an electric circuit when the thread breaks or runs out.

The broad object of the invention is to provide an end detector device which shall be especially efficient and adapted for operation with very fine yarns or threads. Another object of the invention is to construct the end detector in a manner to make it especially well adapted for efficient operation in that it includes construction features for eliminating failure of operation due to vibration by the knitting machine and it also includes features which prevents short circuiting.

The invention is embodied in an end detector device arranged and constructed as hereinafter set forth and as illustrated in the accompanying drawings in which the end detector is shown mounted for operation upon a knitting machine of the type disclosed in my U. S. Patent No. 1,775,298, though it is not limited to that type of machine. In the said drawings

Fig. 1 is a diagrammatic view of a portion of a circular knitting machine with my invention applied.

Fig. 2 is a side view of one form of my improved end detector.

Fig. 3 is an end view thereof.

Fig. 4 is an end view of another form of my end detector.

Fig. 5 is a side view of Figure 4.

Referring to Figure 1, the numeral 6 represents a rotatable central shaft or post of the knitting machine which is mounted on a suitable bearing 7 supported from the bed 8. The shaft is rotated in any suitable manner, not shown, and carries a series of radial arms 9 which support the spindles for the spools 10. Above the arms 9 is another series of radial arms 11 which carry the first end detectors 12, the detailed construction of which is to be explained in detail hereafter.

At the top of the post there is a third series of arms 13 which support circuit closers 14 which are shown diagrammatically and which may be of the construction shown in my U. S. Patent No. 2,013,529. The circuit closers 14 function to close the circuit when there is a knot or obstruction on the yarn or when the yarn breaks. It should be noted that there usually is a considerable distance between the end detectors 12 and the circuit closers 14.

Beneath the arms 9 is a disk 15 from which,

preferably at diametrically opposite points, radiate contact fingers or brushes 16 which are insulated from the disk 15 as at 17 and to which the insulated circuit terminals of the circuit closers 12 and 14 are electrically connected in a well known manner as indicated by wires 18. The wires are shown by dot and dash lines to distinguish them from the lines of the yarn. Mounted on fixed supports 20 through insulating connections 21 is a contact ring 22 with which the fingers 16 have a wiping contact. The ring 22 being stationary and the fingers 16 being rotatable rub along the under edge of the ring and assist in maintaining its surface bright and clean for good electrical contact.

Below the disk 15 there is still another set of arms 23 which carry other end detectors 24 similar to the detectors 12 which are electrically connected to the wires 18 as shown. The electric current is supplied by a wire 25 to the ring 22 hence by way of the wires 18 to all the circuit closers, the other side being grounded as is well known. It is to be understood that when a circuit closer is operated, the circuit is closed and in turn actuates a stop mechanism, not shown, to stop the machine. This is well known in the art. In operation the yarn or thread 26 is passed from the spools 10 upwards through the end detectors 12, thence up over the knot detectors 14, thence down through suitable guides 27, thence down through the detectors 24 to the knitting mechanism, not shown.

I will now describe my improved end detector which is embodied in a very substantial construction to insure rigidity against vibration. At the same time the circuit closing elements are constructed in a manner to make the device very sensitive and adapted for operation with very fine yarns.

Referring to Figures 2 and 3 the end detector consists of a very substantial rectangularly bent bracket consisting of a horizontal supporting branch 30 and a vertical guiding branch 31 having two parallel inclined guides 32, 32 provided with eyelets 33 in substantial alinement with an eyelet 34 in the branch 30. The latter has holes 35 for attachment to the knitting machine.

On top of the branch 30 there is mounted a contact box 36 which is completely closed so as to enclose a leaf spring contact 37 and the contacting heel 38 of a detector lever 39 pivoted in the sides of said box at 40. The detector lever 39 is in the form of a very fine thin steel wire having a hook 41 at its lower end adapted to swing between the guides 32 as shown. It will readily

be understood from the drawings that because of the very short heel as compared to the great length of the wire 39, the latter tends to assume a vertical position under the influence of gravity. 5
5 On top of the contact box there is mounted a circuit terminal 42 suitably insulated as at 43. The terminal is secured at two places 44 and 45 and cannot turn. At 45 the terminal 42 is in electrical contact with the spring 37. The box is 10 secured by a rivet 46 and is prevented from turning by having lips 47 engaging the sides of the bracket 30. Hence it will be noted that this construction is of extreme rigidity, eliminates the loosening of parts due to vibration and prevents 15 short circuiting. A tension device 48 may be mounted on a lateral branch 49.

In operation the thread 26 is passed through the eyelets 33 and 35, the hook 41 of the wire 39 being swung in behind the thread. When the 20 thread runs out, the wire 39 swings forward, the heel 38 contacts with the spring contact 37 and the circuit is closed.

The device is extremely sensitive. Although the wire lever 39 is very much heavier than the 25 heel 38 (see also Fig. 4) it is sufficiently delicate and sensitive so as to give with the thread. It is understood of course by anyone familiar with the operation of a knitting machine that the thread is not pulled through the machine in an 30 exact straight line but that the operation is jumpy so to speak and that at times the wire hook 41 is pulled back into the position shown in the drawing and at times the wire swings slightly forwardly. In other words there is a constant 35 rub of the thread against the wire hook, hence the latter must be thin enough and sensitive enough to prevent uninterrupted operation so long as the thread remains. When, however, the thread breaks the wire lever must instantly swing 40 into circuit closing position. The device illustrated and described fulfills these demands to an extraordinary high degree of perfection.

Figures 4 and 5 illustrate an end detector embodying the same features as above described but 45 arranged for placement in knitting machines where the detector in Figure 2 cannot be used to advantage. Similar parts in Figures 4 and 5 are lettered with the same reference characters as those in Figure 2. In this case there is provided a vertically disposed supporting bracket 50 having three lateral guide arms 51 provided with eyelets 52. The contact box 36 is secured to the bracket 50 back of the thread which passes

through the eyelets 52. The contact terminal 53 is secured to the box and extends to one side of the bracket a considerable distance at right angles. The tension device 48 is mounted on the contact terminal. The contact wire 54 is pivoted 5 in the box at 40 and has a heel 55 adapted to contact the spring terminal 37 to which the fixed terminal 53 is electrically connected by a rivet 56. The upper end of the wire lever 54 has a porcelain covered arm 57 which crosses the path 10 of the yarn 26 which is passed through the three alined eyelets 52. When the thread runs out the wire lever falls outward under the influence of gravity and the circuit is closed between the heel 55 and the spring 37. In Figure 2 the yarn 15 may be led over the tension device before passing through the eyelets 33. In Figure 4 the thread may be passed around the tension device before passing through the two upper eyelets 52. In both cases it will be noted that the eyelets 20 are grouped. One group containing one eyelet and the other group containing two eyelets. This arrangement permits the device to be used with or without tension as is obvious.

I claim:

A stop mechanism of the character described comprising a bracket bent at right angles to form a horizontal and a vertical depending arm, the latter having its lower free end bent at an acute angle in the direction of the said horizontal arm and forming a thread guiding arm, a second thread guiding arm secured to the said vertical bracket arm in parallel relation to the said first named guiding arm, eyelets in the free ends of said guiding arms, a closed contact box 30 secured in non-turnable relation on top of said horizontal bracket arm, an insulated contact spring in said box, a gravity actuated lever pivoted in said box to one side thereof and having a contact heel within the box adapted to make 35 contact with the said contact spring, the lower end of said gravity lever being bent at right angle and adapted to engage a thread passing through the said eyelets between the same to keep the 40 said contact heel in circuit open position within the box, a tension device secured to the said vertical bracket arm above the said two thread guiding arms and an eyelet in the said horizontal bracket arm in substantial alinement with the 45 said tension device and the said two first mentioned eyelets.

JACOB WACHSMAN,
